WASH FOUNTAIN SPRAY HEAD

Howard A. Mullett, Milwaukee, Wis., assignor to
 Bradley Washfountain Company, Milwaukee,
 Wis., a corporation of Wisconsin

Application October 16, 1936, Serial No. 105,896

12 Claims. (Cl. 299—144)

The invention relates to sprayheads for wash-fountains.

In some sections of the country the water contains considerable solids or semi-solids that in time clog the spray orifices of the sprayhead and thus interfere with its efficient operation. Furthermore, these solids collect in the chamber behind the sprayhead and thus change the rate of delivery of the water through the nozzles from that originally intended. In order to obviate these difficulties it is the object of this invention to provide a two piece sprayhead in which the nozzle passages and the chamber behind said passages may be readily cleaned of sediment or foreign particles.

It is a further object of the invention to provide a sprayhead in which the valve for the spraying fluid opens into the chamber provided with the spray orifices, and an impact member is interposed between the valve port and said orifices to prevent water spouting out beyond the confines of the basin into which the sprayhead discharges when the sprayhead parts are in a cleaning position.

25 A further object of the invention is to provide a sprayhead in which the inlet valve has a removable seat member which forms a hold-down means for the spray fixture.

30 A further object of the invention is to provide a multi-part sprayhead in which one of the parts thereof is limited in its movement to a cleaning position by a stop on the supporting standard for said sprayhead.

The invention further consists in the several 35 features hereinafter set forth and more particularly defined by claims at the conclusion hereof.

In the drawings:

Fig. 1 is a vertical sectional view of a spray-head embodying the invention;

40 Fig. 2 is a detail sectional view of parts shown in Fig. 1 in cleaning position;

Fig. 3 is a detail side elevation view of one of the sprayhead parts, parts being broken away;

45 Fig. 4 is a view of a modified form of spray-head parts being broken away and parts being shown in section;

Fig. 5 is a detail sectional view of certain modifications of the sprayhead, the parts being shown 50 in cleaning position;

55 Fig. 6 is a detail side elevation view of one of the parts shown in Fig. 4;

Fig. 7 is a detail sectional view of one of the parts shown in Fig. 1 showing certain modifications;

Fig. 8 is a detail side elevation view of the part shown in Fig. 7;

Fig. 9 is a detail sectional view of another of the parts shown in Fig. 1 showing certain modifications.

Referring to Figs. 1 to 3 inclusive of the drawings, the sprayhead includes two main metal members 10 and 11.

The member 10 is of circular shape formed to provide a base portion 12 and a top portion 13 spaced from said base portion by the integral ribs 10' or spaced columns 14 to form a chamber 10'.

The base portion 12 has a centrally disposed threaded opening 15 therein, an annular upstanding impact portion 16 concentric with said opening and a flat surface 17 extending from said portion 16 to the outer cylindrical edge 18. The portion 12 has a depending annular flange 19 having a threaded outer side 20 which is spaced inwardly from the edge 18.

The top portion 13 is of circular formation with a centrally disposed valve stem mounting boss 21 and a conically inclined outer edge portion 22 having a lower nozzle forming surface 23.

The member 11 is a flanged ring having a 25 threaded base flange 24, a base web 25, an up-standing flange 26, and an outer drip flange 24'. The upper edge of the flange 26 is provided with a plurality of nozzle forming notches 27 which have the same inclination as the surface 30 23 and cooperate therewith when the parts are in assembled position to provide a plurality of downwardly inclined closely associated spray orifices 28. The threaded connection between the

side 20 of the member 10 and the base flange 24 35 permits the parts to be assembled and held in spray forming position, and when so assembled, a yieldable washer 29 may be interposed between the base portions of these parts. For turning the member 11 relative to the member 10 40 one or more holes 30 may be provided in fillets in said member 11 for receiving a spanner wrench or other suitable tool.

A pipe fitting 31 is formed at its upper end 32 to provide a renewable valve seat and is threaded at 33 to removably engage the threaded opening 15 of the part 10, a washer 34 being interposed between said part 10 and a shoulder 35 on said fitting. This fitting has an enlarged bore 36 at its lower end threaded to receive the washing 50 fluid supply pipe 37. This fitting 31 when screwed into the part 10 acts as a hold-down means for bringing the member 10 against the upper end of the standard 47.

A flat face rubber or suitable composition valve 55

38 cooperates with the seat 32 and is removably secured to its stem 39 by a screw 40, said stem having a threaded portion 41 engaging the threaded bore 42 of the boss 21, the upper end 43 of said stem working through a stuffing box 44 of known construction, the exposed end of said stem carrying an operating handle 45. Part of the stem is shown enclosed by a tubular member 46 which is used to carry a soap tray (not shown).

10 The head engages a hollow tubular standard 47 whose upper end seats in an annular groove 48 in the part 10, and at some point below this end it is provided with an annular stop shoulder 49 to limit the movement of the member 11 when 15 it is moved to a cleaning position to prevent the ring falling upon the enameled or other finished surface of the bowl beneath it and also possible deformation of said ring.

With this construction, the turning of the stem 20 39 in the proper direction raises the valve 38 from its seat 32 and allows water to pass into the chamber 10' and thence through the orifices 28 in a downwardly inclined direction and in an annularly spaced series of small streams of low 25 velocity since the volume of the chamber 10' acts to reduce the pressure from that in the supply pipe 37. If the orifices 28 should tend to clog, then the ring member 11 may be turned down to 30 separate the parts of the sprayhead, as shown in Fig. 2, so that the orifices may be readily cleaned. If sediment should collect in the chamber 10' which would tend to reduce its volume and thus increase the pressure of the water through the orifices beyond a predetermined desired value, 35 then the turning down of the ring member 11 to the position shown in Fig. 2 where the edge 27 of said ring member is below the flat surface 17 of the part 10 permits the water flushing out the sediment in the sprayhead chamber 10'. During 40 this flushing operation the impact member 16 prevents the water from the valve controlled opening from spouting out through the opening 50 provided by the parts of the sprayhead in their cleaning position beyond the confines of 45 the basin into which the sprayhead discharges, but it does not prevent an efficient flushing of the chamber 10'. With the parts in assembled formation the drip flange 24' prevents any drip from the nozzles working down along the standard 47 as this drip will fall off the lower edge of 50 said flange.

In some types of washfountains a vent pipe passes centrally through the spray fixture, and in Fig. 4 I have shown my improved sprayhead 55 applied to an arrangement of this kind wherein 51 is the centrally disposed vent pipe, 52 and 53 concentrically disposed pipes forming a water inlet passage 54, the pipe 52 being spaced from the pipe 51. The sprayhead member 55 is similar 60 to the member 10 and is formed to provide a base portion 12' and a top portion 13' spaced from said base portion by the integral ribs or spaced columns 14' to form the chamber 10''.

65 The base portion 12' has a centrally disposed threaded flange portion 15', a flushing surface portion 17' extending to the outer cylindrical edge 18', and a depending annular flange 19' threaded to receive the upper threaded end of the standard 47 and also provides a depending flange having a threaded outer side 20' which is spaced inwardly from the edge 18'.

70 The top portion 13' is of circular formation with a centrally disposed threaded bore 21' for 75 the pipe 53 and a conically inclined outer edge

portion 22' having a lower nozzle forming plain surface 23' similar to the surface 23.

The member 11' is substantially identical with the member 11 and is a flanged ring having the threaded base flange 56, a base web 25', an up-standing flange 26' and an outer drip flange 57, the flange 26' being provided with nozzle notches 27' similar to the notches 27 and which cooperate with the surface 23' to form a plurality of downwardly inclined closely associated spray 10 orifices 28'. The threaded connection between the flange portion 16' and the base flange 56 permits the parts to be assembled and held in spray forming position, and when so assembled, a yieldable washer 29' may be interposed between the 15 base portions of these parts.

The water passing through the passage 54 is controlled in any suitable manner usually through a mixing valve (not shown). If the orifices 28' should tend to clog, then the ring member 11' 20 may be turned down as in the first construction to separate the parts of the sprayhead so that ready access may be had to the parts forming the orifices. If objectionable sediment should collect in the chamber 10'', then the turning 25 down of the member 11' to bring its edge 27' below the flat surface 17' permits the water flushing out the sediment in said chamber.

Certain advantages of the invention may be obtained where the spray orifices are formed 30 wholly in either one or the other of the parts 10 and 11. In Fig. 7 the part 58 is similar to the part 10 previously described except that downwardly inclined spray orifices 59 are drilled in the lower edge portion of the part 22'', similar to 35 the part 22, and the part 60, similar to the part 11, has a smooth edge similar to the edge 23 engaging the smooth edge 61 of said part 58. In Fig. 9 the part 62 is similar to the part 11 previously described except that downwardly inclined spray orifices 63 are drilled adjacent the 40 smooth upper edge 64 of the upstanding flange of said member, said edge adapted to seat against the smooth surface 23 of the part 10. In both of these constructions the advantages of flushing 45 the chamber between the sprayhead parts is obtained when the parts are in a cleaning position.

In the modification shown in Figs. 5 and 6 the part 65 is generally similar to the part 10 except that the bottom portion 66 with its depending 50 flange 67 does not have a part extending therefrom and instead of a smooth edge for the nozzle forming portion, the nozzle forming notches 68, similar to the notches 27, are formed in this edge. A threaded ring member 69 has a threaded flange 55 70 to engage the threads of the flange 67 and a flat upper surface 71 which when screwed down to a cleaning position, forms an extension of the flat flushing surface portion 72 of the part 65 as shown in Fig. 5. In this form the outer edge 60 73 of the member 69 is a conically inclined flat surface which cooperates with the notches 68 when the parts are in assembled position to form downwardly inclined closely associated spray orifices similar to 28. The part 69 has a peripheral 65 depending flange 74 to prevent drip running down the sides of the standard 47. This last described construction has the same advantages as that of the first described construction as regards the cleaning of the spray orifices and the flushing 70 of the pressure reducing chamber 74.

The sprayhead above described is used in connection with washfountains of the general type shown in U. S. Patent No. 1,477,189, of December 11, 1923, to Louis Schlesinger wherein the small 75

streams of low velocity water are directed downwardly toward the outer side of the cylindrical basin.

I desire it to be understood that this invention is not to be limited to any particular form or arrangement of parts except in so far as such limitations are included in the claims.

What I claim as my invention is:

1. A sprayhead for washfountains comprising separable members formed to provide a chamber having downwardly inclined peripheral spraying orifices, one of said members having spaced top and bottom walls, the other of said members being a ring member movable to a cleaning position to permit flushing of said chamber, and means for introducing water into said chamber, the movement of said ring member to a cleaning position not interfering with the operation of said last named means. 10
2. A sprayhead for washfountains comprising a pair of separable members formed to provide a chamber having downwardly inclined peripheral spraying orifices, one of said members having spaced top and bottom walls, the other of said members being a ring member movable to a cleaning position to permit flushing of said chamber, means for introducing water into the central portion of said chamber, the movement of said ring member to a cleaning position not interfering with the operation of said last named means, and means for obstructing direct passage of the water from said introducing means through said chamber when said members are in a cleaning position. 20
3. A sprayhead for washfountains comprising a pair of separable members formed to provide a chamber having downwardly inclined peripheral spraying orifices, one of said members having spaced top and bottom walls, the other of said members being a ring member movable to a cleaning position to permit flushing of said chamber, means for introducing water into the central portion of said chamber, the movement of said ring member to a cleaning position not interfering with the operation of said last named means, said first mentioned member having a wall portion surrounding the central portion of said chamber to obstruct direct passage of the water from said introducing means through said chamber when said members are in a cleaning position. 30
4. A sprayhead for washfountains comprising separable members formed to provide a chamber and divided along their peripheral portions, said portions having abutting edges cooperating to form a plurality of downwardly inclined spraying orifices, and means for introducing water into said chamber. 40
5. A sprayhead for washfountains comprising separable members formed to provide a chamber and divided along their peripheral portions, said portions having abutting edges cooperating to form a plurality of downwardly inclined spraying orifices, one of said members being a ring member movable to a cleaning position to permit flushing of said chamber, and means for introducing water into said chamber. 50
6. In a sprayhead for washfountains, the combination of a pair of separable members formed to provide a chamber having downwardly inclined peripheral spraying orifices, a standard engaging one of said members, the other of said members being a ring member movable downwardly over said standard to a cleaning position, means for limiting the movement of said last named member, and means for introducing water into said chamber, the movement of said ring member to a cleaning position not interfering with the operation of said last named means. 5
7. In a sprayhead for washfountains, the combination of a pair of separable members formed to provide a chamber having downwardly inclined peripheral spraying orifices, a standard, means for clamping one of said members against the top of said standard, the other of said members being a ring member movable downwardly over said standard to a cleaning position. 10
8. In a sprayhead for washfountains, the combination of a pair of separable members formed to provide a chamber having downwardly inclined peripheral spraying orifices, a standard, and means including a removable inlet valve seat member for securing said sprayhead to said standard. 15
9. In a sprayhead of the character described, the combination of a member having spaced plate portions to form top and bottom walls, a ring member movably mounted on the bottom wall portion of said first named member and cooperating therewith to form a chamber provided with downwardly inclined peripheral spraying orifices, means for supplying water to said first named member, said ring member being movable to a position to permit free passage of water between the walls of said first member for flushing said chamber. 20
10. In a sprayhead of the character described, the combination of a member having spaced plate portions to form top and bottom walls, a ring member movably mounted on the bottom wall portion of said first named member and provided with an upstanding wall engageable with the outer edge portions of said top wall, said engaging portions of said members being formed to provide a plurality of downwardly inclined spraying orifices. 25
11. In a sprayhead of the character described, the combination of a member having spaced plate portions forming top and bottom walls, a valve controlled water inlet to said member, the bottom wall of said member having an exteriorly threaded flange, a threaded ring member engaging said threaded flange and provided with an upstanding wall turnable into engagement with the outer edge portions of said top wall, said engaging portions of said members being formed to provide a plurality of downwardly inclined spraying orifices. 30
12. A sprayhead for washfountains comprising a body member having a chamber provided with separated wall portions, the edge of one of said wall portions being downwardly inclined and a removable ring member closing the space between said wall portions and having a surface abutting the inclined edge of said wall portion and provided with orifice forming notches. 40

HOWARD A. MULLETT.
